BARTON H. COFFEY, OF ELIZABETH, NEW JERSEY

ART OF REFRIGERATION

Original application filed August 9, 1920, Serial No. 402,403. Divided and this application filed November 17, 1925. Serial No. 69,623.

My invention relates to improvements in the art of refrigeration and particularly to the compression method of refrigeration in which is employed the evaporation of liquids 5 to effect the heat flow. In this method the refrigerating liquid such as sulphur dioxide, ammonia, carbonic acid or the like at a given temperature and corresponding pressure flows into a lower pressure and corresponding 10 temperature, evaporation takes place at this temperature, the required heat being drawn from the liquid or refrigerant and the cooling body, thus lowering their temperatures. The vapor formed is then compressed and 15 condensed at the original pressure and temperature, the heat being absorbed by a cooling fluid. The cycle thus reveals a closed circuit of refrigerating liquid and vapor in contact but not mixed, one section of which 20 is kept at a high pressure, and the other at a low pressure accompanied by two heat currents at different thermal levels and in opposite directions, i. e. at the lower level the heat current passes into the refrigerating liquid 25 and at the higher pressure the heat current passes from it, all of which is in conformity with the recognized laws of thermodynamics.

Though rotary compressors have been proposed the compression in the cycle has heretofore, to my knowledge, been accomplished only with reciprocating compressors of various types possessing the complications and objections inherent in devices of this character. The expansion has generally been through orifices or cocks which divides the circuit and direct from the high to the low pressure sections, thus losing the external energy possessed by the expanding vapor.

40 The object of my invention is to eliminate the compressor expansion cock and divided circuit to save the energy of the expanded vapor thus producing the carnot cycle, and to attain the desired effect by gradually producing the required variation of pressure and temperature in an undivided closed circuit of refrigerating liquid and vapor (which thus itself performs the compressing function) enclosed in a conduit free from valves, 45 expansion cocks and compressors. I attain

this object by the form of my device illustrated in the accompanying drawings but modifications may be made therein without departing from the spirit of my invention.

This application is a divisional application of Letters Patent No. 1,565,795, dated December 15, 1925.

I accomplish this object by the device illustrated in the accompanying drawings in which,

55 Figure 1 is a preferred form of my device, and

60 Figure 2 is a diagrammatic representation of the cycle of operation to explain clearly the phases which it includes.

65 Figure 3 is a side view of Fig. 2.

Similar characters of reference refer to similar parts throughout the several views.

In the device here illustrated, I present a method of applying to the art of refrigeration the theorem that in a continuous conduit through which liquid and vapor is flowing adiabatically the sum of the heat energy and kinetic energy at every section is constant, in other words, variations of pressure and temperature may exist of a magnitude corresponding to variations in velocity which in turn can be produced by variations in the area of successive cross sections of the conduit. As is obvious, the conduit may be a closed circuit without affecting this law, and if energy be introduced in the conduit sufficient to overcome frictional resistances, plus the energy equivalent to the net work of adiabatic compression the circulation becomes continuous and it is apparent that if low temperature heat is absorbed at the low pressure point of the circuit and if it, plus the heat of adiabatic compression and friction and other heat added is discharged at the high pressure point a refrigerating cycle of the compression type results.

80 The closed circuit includes a pipe or conduit 1 which carries the refrigerant. A centrifugal pump 2, having a rotor 3 which is driven by a motor 4 is inserted in the circuit. Surrounding the rotor 3 is a circular casing 85 5 having an axial inlet port 6 and an annular discharge chamber 7 from which the refrigerating medium is discharged at the port 8

100

to the conduit 1. As the pressure exerted by the rotor 3 varies directly with the mass and square of lineal velocity and inversely as the radius of curvature, it is evident that the rotating mass of liquid within the casing 3 can thus be made to show within itself any reasonable variations of pressure from center to circumference.

The refrigerating liquid or medium enters 10 the rotating member 3 shown in full line at its axis or point of zero pressure 6. The rotating member 3 is preferably in the form of a bladed hollow drum fitting the entering conduit 1 at port 6, and is driven by a motor 15 4 through the medium of a shaft 9, and is preferably provided with suitable discharge orifices 10 at its circumference, open to the annular space between the casing 5 and the rotor 3 and thence to the annular discharge 20 chamber 7 which may be of circular or volute shape. The circuit of the cooling medium is through the pipe 1 and the brine cooler of any desired type 11, to the axial admission port 6 in the rotating member 3 and thence 25 through the orifices 10 around rotor 3 to the annular chamber 7 from which it is again discharged into the pipe 1 through the outlet 8 which may be tangential to the annular chamber 7. Within the casing 5 I provide 30 a circumferential annular space or chamber 12 surrounding the rotating member 3 through which cooling water circulates, thus constituting the chamber 12 a condenser.

The system is supplied with refrigerating 35 liquid and the rotor 3 set in motion, the liquid within the rotor will be rotated producing compression by centrifugal force which will progressively increase from the center of the rotor to its periphery, thus setting up 40 various pressure within the body of the liquid. As the liquid leaves the casing 5 at the discharge port 8, positioned near the circumference of the rotor 3, the pressure at that point will be greater than at the axial port of entry 6, whereby a circulation will be established in the circuit. If a small portion 45 of the liquid is withdrawn, space will be provided for evaporation, and heat supplied by the cooler 11 will be drawn off by the condenser 12 and a refrigerating cycle results as 50 above described.

The principle of operation is illustrated in Figure 2 and Figure 3, in which the closed circuit includes two U-shaped pipes or conduits 14, 15. The conduit 15 is fixed in position on supports 16, 17. The U-sections are joined together at 18, 19 to rotate with relation to each other, as by inserting the ends of U-section 14 in the ends of U-section 15 as 55 shown. Therefore 20, 20 will be an axis about which U-section 14 may be rotated as it is constructed sufficiently smaller than U-section 15 so that it may pass therethru.

A motor 21 is geared to the section 14 60 to rotate it about the axis 20, 20.

The conduit 14, 15 contains a liquid refrigerant which does not completely fill the conduit. As the U-section 14 is rotated by the motor 21 centrifugal force will cause the maximum pressure to occur in the base part 70 of the U-section 14.

In order to circulate the liquid a pump 22 is inserted in the system at the base of section 14. In order to circulate the refrigerant the pump need only overcome the unbalanced pressure in the legs 14^a and 14^b of the U-section 14, due to greater density in the leg 14^a caused by vapor condensation in the condenser 23.

The liquid at maximum pressure due to 80 rotation of section 14 by motor 21 is forced by pump 22 in the direction of the arrows to circulate in the closed system 14, 15. As the liquid flows toward the center line of rotation 20—20 the pressure will decrease with a 85 consequent decrease in temperature and increase in vapor. This is diagrammatically shown by the increasing width of lines a. On entering section 15 evaporation stops 90 until cooler 24 is reached in which brine circulates. The liquid in the conduit absorbs heat from this brine. Passing thru the cooler the liquid flows into the U-section 14 where the pressure gradually increases and the vapor content decreases due to centrifugal 95 force caused by the rotation of section 14. This is shown by the decreasing width of lines a. At the base of U-section 14 is a condenser 23 which condenses all vapor in 100 the refrigerant liquid as it passes to the pump 22.

The deviating centrifugal force acts precisely as does gravitational force as described in my co-pending application Ser. No. 69,624, with one exception; the intensity 105 of centrifugal force can be controlled. It is obvious that the pressure at any point in the leg 14^a is greater than at the line 20—20 and that a point could be selected to give a pressure difference equal to that imposed 110 upon the pump 22. As the conduit 15 is stationary, no centrifugal effect exists and the pressure of the evaporator 24 is constant 115 throughout.

The fundamental principle of this method consists broadly in setting up various pressures in an integral body of refrigerating liquid in motion supplying low temperature heat to the system at the points of low pressure and withdrawing high temperature heat 120 at points of high pressure, the liquid serving as a transporting agent to move the vapor thus formed from point to point and to compress it all in exact accordance with the theoretical compression refrigeration cycle. 125 In my system the heat transfer surfaces, the pressures and the brine temperature, the cooling water, the refrigerating liquid circulation and the revolutions of the rotor will all be so proportioned to the quantity of low tem- 130

- perature heat supplied and its temperature, that the refrigerating liquid leaving the condenser will be entirely free from vapor in suspension, at or below the temperature corresponding to the maximum pressure in the system, in other words, the heat in the liquid leaving the condenser will be in the sensible form only. As the liquid passes on, the pressure grows less and vapor will form, withdrawing heat from the liquid in the latent form in sufficient quantity to make pressures and temperatures conform arriving at the brine cooler with minimum pressure and corresponding temperature, heat will be received at constant temperature accompanied by a proportionate formation of vapor containing latent heat in quantity to balance that received. As the liquid passes on it enters the zones of increasing pressure with this added quantity of vapor in suspension.
- Having thus described my invention what I claim is:
1. In a device of the character described, a continuous conduit of uniform constant cross-sectional area, fluid circulating means in said conduit, a cooler operatively positioned with respect to said conduit, a refrigerant in said conduit, and a condenser for cooling said refrigerant and means for producing variations of pressure and temperature in the refrigerant by centrifugal force.
  2. In a refrigerating device, the combination of a valveless conduit, a refrigerant in said conduit, means to compress said refrigerant by centrifugal force, means to cool said refrigerant and a cooler adjacent said conduit whereby heat in said cooler may be absorbed by said refrigerant.
  3. In a device of the character described a closed conduit having two conduit sections, one of said sections being fixed and the other of said sections being mounted to rotate on said first section and condenser means operatively connected with said conduit.
  4. In a device of the character described the combination of a closed conduit of two sections, one said section being fixed, the other said section being mounted rotatably on said first section, means to rotate said section, a pump mounted in said rotatable section and condenser means operatively connected with said conduit.
  5. In a device of the character described the combination of a closed conduit having two sections, one of said sections being fixed and forming a journal bearing the other of said sections being rotatably mounted on said first section, means to rotate said second section, a compression pump in said conduit, condenser means operatively connected to said second section and a cooler operatively connected to said first mentioned section.
  6. In a refrigerating apparatus, the combination of an endless closed conduit, a refrigerant circulating therein and comprising a mixture of liquid refrigerant and its vapor, centrifugal means for producing a zone of high pressure and a zone of low pressure in the refrigerant, said variations of pressure being produced by centrifugal force alone, a condenser and a pump adapted to circulate the refrigerant.
  7. In a refrigerating apparatus, the combination of a continuous conduit having two sections, one of which sections is rotatable whereby centrifugal force is generated to produce variations of pressure and temperature in a refrigerant therein, means for circulating the refrigerant and a condenser.
  8. In a refrigerating system the combination of a conduit, a refrigerant therein, centrifugal means adapted to produce pressure variations in the refrigerant by centrifugal head, a condenser and means for circulating the refrigerant in the conduit.
  9. In a refrigerating system, the combination of a source of low temperature external heat, a condenser, means for supplying the net negative work of the cycle, a refrigerant, and means for producing pressure variations within the refrigerant by centrifugal head.
- In testimony whereof I affix my signature.
